[57] CLAIM

The ornamental design for a child's growth measuring and registering unit, as shown and described.

DESCRIPTION

FIG. 1 is a front elevational view of a child's growth measuring and registering unit showing our new design; FIG. 2 is a right side elevational view thereof, the left side being a mirror image thereto;

FIG. 3 is a fragmentary front elevational view of the simulative deer's head on an enlarged scale;

FIG. 4 is a rear elevational view of FIG. 3;

FIG. 5 is a right side elevational view of FIG. 3;

FIG. 6 is a fragmentary front elevational view of another embodiment of our new design of FIGS. 1-5, the remaining views thereof being substantially like those of FIGS. 1-5.
